CLAIM

The ornamental design for an exit light fixture, as shown.

DESCRIPTION

FIG. 1 is a top left perspective view of a first embodiment of the exit light fixture of the present design;

FIG. 2 is a front elevational view thereof;

FIG. 3 is a right side view thereof;

FIG. 4 is left view thereof;

FIG. 5 is a top view thereof;

FIG. 6 is a bottom view thereof;

FIG. 7 is a top left perspective view of a second embodiment of the exit light fixture of the present design;

FIG. 8 is a front elevational view thereof;

FIG. 9 is a right side view thereof;

FIG. 10 is left view thereof;

FIG. 11 is a top view thereof; and,

FIG. 12 is a bottom view thereof.

In the drawings, the broken line showing of the rear portion of the exit light fixture forms no part of the claim.
